UNITED STATES PATENT OFFICE.

LOUIS JUDELSON, OF NEW YORK, N. Y.

WASHING-MACHINE.

1,090,214.

Specification of Letters Patent. Patented Mar. 17, 1914.

Application filed August 8, 1911. Serial No. 642,992.

To all whom it may concern:

Be it known that I, LOUIS JUDELSON, a citizen of the United States of America, residing at 159 West Twenty-fourth street, 5 New York city, in the county and State of New York, have invented certain new and useful Improvements in Washing-Machines, of which the following is a specification.

My invention relates to improvements in 10 washing machines of the type employing an outer casing, and an inner, perforated, revoluble, cylinder wherein the articles to be washed are alternately rotated in one direction, and in the other while being subjected to the action of wet steam. The outer 15 casing and inner cylinder are usually constructed of copper as the material most suitable for the purpose, and heretofore the outer cylinder has been in the form of a drum open at both ends and having a header 20 of cast iron or like material closing each of the ends. One of the disadvantages in a construction of the kind referred to is that when it is necessary to repair the outer casing, either or both the iron headers must be taken out, resulting practically in a disruption of the casing, inasmuch as the headers are firmly riveted to the latter. Another 25 disadvantage is found in the fact that when leaks develop between the copper casing and the iron headers, it is impossible to use solder to repair these leaks as the metals to be soldered together are unlike. A further 30 disadvantage in the constructions heretofore employed has been the practical impossibility of providing an outer casing which would effectually prevent the leakage 35 of steam therefrom.

The object of my invention is to provide 40 a washing machine wherein the several disadvantages above referred to as inhering in present structures are obviated, which improved washing machine may be readily assembled and disassembled and wherein the 45 outer casing is proof against leakage of steam.

The preferred form of the invention is 50 illustratively exemplified in the accompanying drawing, wherein—

55 Figure 1 is a side elevational view of my improved washing machine, the cover being closed down on the outer casing; Fig. 2 is an end elevation of Fig. 1 looking toward the right; Fig. 3 is a cross sectional view taken on the line 3—3 of Fig. 1, representing the cover partly open; and Fig. 4 is a

cross sectional view taken on the line 4—4 of Fig. 1.

In carrying my invention into practice I preferably form the outer casing as a complete drum, that is to say, it consists of the body portion 10, the end members 11 and the sliding cover 12 all of like metal such as copper. To prevent leakage of steam between the casing and end members, I preferably 60 form the joint therebetween as shown in Fig. 4 from which it will be noted that the material of the body portion 10 is bent upon itself to form the overlapping members 10^a and 10^b, and each end member 11 65 is provided with the lap 11^a. Interlocking 70 each end member 11 with the body portion of the casing is a separate locking member which comprises the web portion 13, the overlapping flange members 13^a and 13^b 75 which engage the overlapped members 10^a and 10^b of the body, and the overlapping members 13^c and 13^d which engage with the overlapped part 11^a of the end member. The overlapped ends 10^a and 10^b of the body 80 together with the web portion 13 and the overlapped flange members 13^a and 13^b project beyond the ends 11 and form an annular support of five thicknesses of metal to which a suitable header A of cast iron or other like 85 material, is removably attached by means of the bolts 14. The headers serve to strengthen and give rigidity to the casing 10 but may be removed very readily by removal of the bolts 14. Each header is provided 90 with a strengthening rib 15, and supported in a bearing 16 in one of the headers is a shaft 17 driven from any suitable source of power and adapted to rotate the inner cylinder. Upon one of the headers is 95 formed a pair of bosses 18 designed to support mechanism (forming no part of the present invention and not herein illustrated) by which the direction of rotation 100 of the inner cylinder is reversed at intervals.

The inner cylinder, which is revolved by the shaft 17 is designated 19, a fragment only of this cylinder being shown in cross section in Fig. 3. The cylinder 19 wherein 105 the articles to be washed are placed and subjected to the action of wet steam, is provided with a plurality of perforations 20 through which steam (or water if desired) may pass in either direction.

One of the important features of my invention relates to the manner of preventing

leakage of steam out of the casing 10 when the cover 12 has been closed by means of the handle 21. The cover is slideable in curved guides 22 secured to the periphery of the casing 10, and the edge which engages the edge of the casing 10 is preferably formed as shown in Fig. 3. The cover 12 is first bent upon itself as at 12^a and is then bent in the reverse direction as at 12^b, then is carried along to form the substantially straight web 12^c, then again bent upon itself as at 12^d and finally terminates in the hook like end 12^e. The edge of the cover, formed as just described, is intended to engage, and co-15 operate with, the suitably formed edge of the casing 10 to prevent leakage of steam therefrom. The edge of the casing 10 is bent upon itself as at 10^c then carries along as a straight web portion 10^d and then bent 20 as at 10^e to form a wall parallel to the wall 10^c. When the cover is closed down on the casing the space between 12^a and 12^b is occupied by the thicknesses of metal 10 and 10^c, the space between 10^c and 10^e is occupied by 25 the portions 12^b, 12^c and 12^d and the hook shaped end 12^e lies over and engages the upper edge of the wall 10^e, in this manner forming an interlocking joint past which steam cannot escape. It will, of course, be 30 understood, that the casing 10 is but one-half a cylinder, the cover forming the other half, and that, although not illustrated in the drawing, the edges of both casing and cover opposite those shown in the drawing 35 are constructed similarly to the illustration

of Fig. 3 so that a leak proof joint is provided at both edges of the cover and casing.

The entire structure is usually supported on legs 23 resting on the floor 24.

Having now described my invention, what 40 I claim as new and desire to secure by Letters Patent is:—

A washing machine casing, embodying therein a substantially cylindrical sheet metal body portion having the material at 45 the ends thereof doubled upon itself there being a space between the two layers of material, a circular sheet metal end member set in from each extremity of the body portion, the edge of each end member adjacent the 50 body portion being bent on itself to form two layers of material spaced from each other, a locking member for securing each end member to the body portion, each of said locking members comprising an angular sheet of metal having its opposite ends bent upon themselves whereby one of said ends engages between the spaced layers of 55 material of the end member and the other end engages between the spaced layers of material of the edge of the body portion, and an annular cast metal header secured to said body portion immediately adjacent and on the outer side of one of the end members.

In testimony whereof I have affixed my 60 signature in presence of two witnesses.

LOUIS JUDELSON.
